DELIVERY ROLL FIXTURE

Samuel N. Hope, Wauwatosa, Wis., assignor to
Griffith-Hope Company, West Allis, Wis., a cor-
poration of Wisconsin

Application December 10, 1934, Serial No. 756,818

5 Claims. (Cl. 242—55.2)

The invention relates to dispensing fixtures for rolls of sheet material, such as paper towels and toilet paper.

An object of the invention is to provide an improved dispensing fixture for rolled sheet material, whereby to reduce the number of parts and to simplify manufacture and assembly.

The invention further consists in the several features hereinafter described and claimed.

10 In the accompanying drawing, illustrating two specific embodiments of the invention,

Fig. 1 is a top view of a dispensing fixture constructed in accordance with the invention, parts being broken away and parts being shown in section;

Fig. 2 is a sectional view of the fixture, taken generally along the line 2—2 of Fig. 1;

Fig. 3 is a rear view of one end portion of the fixture, parts being broken away and parts being shown in section, and

Fig. 4 is a view similar to Fig. 2, but showing a modified form of the invention.

In the drawing, 10 designates a rectangular base or support having marginal flanges 11 which are adapted to engage a wall 12, usually a vertical wall. The base 10, preferably a sheet metal stamping, is secured to the wall 12 by screws 13 which pass through openings 14 formed in dished portions 15 of the base.

30 The base construction is similar to that shown in my joint Letters Patent with Nicholas Tuszynski, No. 1,955,067, for Roll towel fixture, issued April 17, 1934.

In that form of the invention shown in Figs. 35 1 to 3, the base 10 has formed therein near each end a pair of aligned guide slots 16 slidably receiving therethrough the spaced parallel legs of a stirrup-shaped spring 17, preferably formed of resilient wire, the free ends of the legs projecting forwardly from the base member.

A pair of sheet metal roll-supporting arms or brackets 18 have end portions interposed between the spaced legs of the respective springs, and each has inturned side flanges 19 which are 45 provided with openings 20 to receive hooks 21 formed on the ends of the springs. At their inner corners the flanges 19 have rounded portions 22 substantially concentric with the openings 20. Between the slots 16 and the adjacent end edges 50 of the base 10 aligned ribs 23 are embossed on the base member, and the edges of the flanges 19 of the arms are fulcrumed on these ribs.

The legs of each spring 17 are retracted or urged inwardly by an arched intermediate portion 24 of the spring having a bearing against

the inner face of the base. By this construction, the arms or brackets 18 are spring-urged toward each other about their fulcrumed bearing on the ribs 23. Each spring is confined against lateral movement by the slots 16 in which they fit, the spring legs being at the outer ends of the slots. The tempering of each spring may be confined, if desired, to the arched intermediate portion 24.

At their free end portions, the arms or brackets 18 are provided with rounded embossments or 10 hubs 25 secured in place by marginal flanges 26 on the arms. The embossments 25 are adapted to enter the opposite hollow ends of a roll 27 of sheet material to be dispensed, such as paper toweling or toilet paper, the roll being rotatably 15 mounted on the embossments. In the present instance, the roll is shown to be provided with a tubular core 28 of paper or other suitable material. An annular shoulder 29 on each embossment or hub is engageable with the end of the roll 20 and is urged thereagainst by the action of the spring 17 to frictionally retard the rotation of the roll.

In the modified form of arm mounting shown in Fig. 4, the wire spring 17' has its retractable 25 legs at the inner sides of the side flanges 19 of the arm or bracket 18, and the legs have outwardly projecting hooks 21' at their forward ends received in the openings 20 of the arm flanges. The spring legs slidably fit in aligned slots 16' 30 formed in the base 10', and are disposed at the inner ends of these slots.

To install a roll on the fixture, it is only necessary to move apart the arms or brackets 18 against the action of their springs, admit the roll 35 between the brackets, and then permit the embossments 27 of the spring-urged arms to enter the opposite ends of the core. To remove an exhausted core is equally simple.

As indicated by dotted lines in Fig. 1, each arm or bracket 18 can be swung inwardly to a position close to the base 10, to thereby permit compact packaging of the fixture.

When the fixture is in use, sheets are torn off the roll as needed, the roll being prevented from turning too freely by the frictional engagement of the spring-pressed arms or brackets 18 with the ends of the roll. The resilient mounting of the arms 18 permits rolls to be properly accommodated on the fixture notwithstanding variations in roll width met with in manufacture.

The fixture requires but relatively few parts and is of such character as to permit economical manufacture.

What I claim as new and desire to secure by Letters Patent is:

1. A dispensing fixture for paper rolls and the like, comprising a base having an apertured wall, spaced roll-supporting brackets on said base for receiving a roll therebetween, at least one of said brackets being swingable with respect to the base, and a spring engaging said base and having retractable legs projecting forwardly through said base and connected to said bracket for urging said swingable bracket toward the roll.
- 5 2. A dispensing fixture for paper rolls and the like, comprising a base having an apertured wall, spaced roll-supporting brackets on said base for receiving a roll therebetween, at least one of said brackets being swingable with respect to the base, and a spring engaging said base and having legs projecting forwardly through said base and provided with hooked ends pivotally engaging said swingable bracket for urging said bracket toward the roll.
- 10 3. A dispensing fixture for paper rolls and the like, comprising a base having an apertured wall, spaced roll-supporting brackets on said base for receiving a roll therebetween, at least one of said brackets being swingable with respect to the base, and a spring engaging said base and having legs
- 15 projecting forwardly through said base and provided with end portions pivotally connected to said bracket for urging said swingable bracket toward the roll.
- 20 4. A dispensing fixture for paper rolls and the like, comprising a base having a wall with aligned slots, spaced roll-supporting brackets on said base for receiving a roll therebetween, at least one of said brackets being swingable with respect to said base, and a wire spring engaging said base and having legs projecting forwardly through said slots and provided with hooked ends pivotally engaging said swingable bracket for urging said bracket toward the roll, said legs being disposed at opposite ends of said slots for confining said legs against lateral shifting.
- 25 5. A dispensing fixture for paper rolls and the like, comprising a base, spaced roll-supporting brackets on said base for receiving a roll therebetween, at least one of said brackets being swingable with respect to said base, and a bracket securing spring engaging said base and having portions pivotally engaging said bracket for holding said bracket on said base and for urging said swingable bracket toward the roll.
